United States Patent Office.

STAFFORD A. DU BOIS, OF CHICAGO, ILLINOIS.

Letters Patent No. 79,329, dated June 30, 1868.

IMPROVED SKATE.

The Schedule referred to in these Letters Patent and making part of the same.

TO ALL WHOM IT MAY CONCERN:

Be it known that I, STAFFORD A. DU BOIS, of Chicago, in the county of Cook, and State of Illinois, have invented a new and useful Improvement in Skates; and I do hereby declare the following to be a full, clear, and exact description of the same, reference being had to the accompanying drawings, and the letters and figures marked thereon, which form a part of this specification, and in which—

Figure 1 represents a side elevation of my improved skate applied to a boot, and

Figure 2 a bottom view of the same.

The nature of my invention consists in making the skate of two separate and distinct short skate-irons, instead of one long one, as heretofore; and it further consists in a novel method of fastening the skate in two separate parts to the sole of the boot.

To enable those skilled in the art to manufacture and use my invention, I will proceed to describe the same with particularity.

The same letters of reference represent the corresponding parts in the different figures.

A and B represent the two skate-irons, which may be made longer or shorter, in proportion to the length of the foot, according to the convenience of the wearer, and the bottom of the irons may be made in any known form, or the irons may be made rounding at both ends, in the form of a rocker, or in any of the ordinary shapes of skate-irons. The irons are rigidly attached to metallic blocks or frames, C and D, by means of the rivets or screws E, so as to be held firmly in place. There are also plates F and H, which are made to fit to the sole of the boot, and are either made a part of the blocks C and D, or are made of separate pieces, and rigidly and firmly attached thereto.

The plate F is formed to fit the sole of the heel of the boot, and has flanges, I, which extend up the side of the heel-sole, with a pointed flange, J, attached to the front flange, that is pressed into the front of the heel-sole. There is also a thumb-screw, K, which screws through the rear flange, I, and into the heel-sole of the boot. By these flanges, and their attachments, the heel-skate is firmly attached to the heel of the boot.

The front skate is firmly attached to the sole of the boot by means of thumb-screws L, which screw through the flanges M, and into the sole of the boot, as shown in fig. 2. The flanges M are a part of or are firmly attached to the plate C, and extend up far enough to keep the boot from moving laterally, and to hold the thumb-screws L. The front skate may be attached to the foot by means of straps buckled around the foot, but I prefer the thumb-screws and flanges, as the straps not only confine the feet, and cramp them so that they are more unmanageable, but make them sore and lame, while this method of fastening leaves the feet entirely free.

Making the skate in two parts, or making two separate skates for each foot, gives much more freedom to the foot, and enables the skater to turn in any direction with much greater ease.

Having fully described the construction and operation of my invention, what I claim, and desire to secure by Letters Patent, is—

1. A skate, made in two separate and distinct parts, one to be attached to the heel of the boot, and one to the sole thereof, substantially as herein set forth.
2. In combination with the plates H and F of the skate, I claim the flanges M and I, and the thumb-screws L, when constructed and operating substantially as described.

Witnesses:

L. L. COBURN,
MAX RAPPINT.
